(57) CLAIM

I claim the ornamental design for a gaming control, as shown and described.

DESCRIPTION

FIG. 1 is a front perspective view of a gaming control showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view in which an exercise cycle is shown in broken lines to illustrate an example environment; and,

FIG. 9 is an enlarged view of the encircled portion in FIG. 8. The broken lines in the figures show portions of the gaming control which form no part of the claimed design.

The broken lines shown in FIG. 8 are for environmental purposes only and form no part of the claimed design.

The dot-dash broken lines encircling portions of the claimed design that are illustrated in enlargements form no part of the claimed design.
